UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING-MACHINE BINDER.

1,275,159.

Specification of Letters Patent. Patented Aug. 6, 1918.

Application filed August 21, 1914. Serial No. 857,805.

To all whom it may concern:

Be it known that I, ALBERT H. DE VOE, a citizen of the United States, residing at Westfield, in the county of Union and State 5 of New Jersey, have invented certain new and useful Improvements in Sewing-Machine Binders, of which the following is a specification, reference being had therein to the accompanying drawings.

10 This invention has for its object to provide a binder which is simple and inexpensive in construction and which is capable of delivering a binding tape accurately to a body fabric whose edges are formed with 15 scalloped or abrupt curves or angles as in the buttonhole flaps of certain classes of shoes or slippers having projecting tongues formed with the buttonholes, and in certain other articles. The binder is preferably 20 constructed of a sheet metal blank bent over upon itself longitudinally to form a base portion and an overhanging portion of single thickness with a rounded connecting portion formed with transverse tape-slots 25 through which a tape may be threaded to contact alternately with the outer and inner faces of said rounded portion and presented from the exterior of said rounded portion through a notch at the delivery end thereof 30 to the edge of the body fabric to which it is secured by stitching.

In the drawings, Figure 1 is a perspective view of a portion of a sewing machine provided with a binder constructed in accordance with the present improvement. Fig. 2 is a top plan view, Fig. 3 a bottom plan view, Fig. 4 a side elevation and Fig. 5 a rear end elevation of the binder detached.

The body of the binder is shown formed 40 of a single piece of sheet metal which is bent over upon itself longitudinally to form the base portion 1, the overhanging portion 2 and the rounded intermediate tape-guiding portion 3 forming between them a substantially laterally closed channel, the portion 3 having a flat rearward extension 4 and the parts 1 and 2 having the spaced and overlapping forward extensions 5 and 6 separated by a central notch 7 at the delivery end 45 of the rounded portion 3. The shell or single wall of the binder is cut at an angle to its longitudinal axis to form a beveled delivery end portion. A binding strip inserted 50

through one or more incisions in the wall and passed through the notch 7 formed by 55 the beveled end may be inverted. Thus a strip led to the stitching point at an angle to the line of feed may be turned inside out and applied to a body fabric together with which it moves in parallelism with the line 60 of feed.

The intermediate portion 3 is provided with a series of transverse tape-apertures or slots 8, 9, 10 and 11, the slot 8 being disposed closely adjacent the delivery end of the 65 binder and said slot, with the one next it, being preferably backwardly inclined as represented more particularly in Figs. 2, 3 and 4. The extensions 5 and 6 terminate in the lateral guide-pins or projections 12 and 13 which are shown disposed at different 70 distances from the bottom of the notch 7 and are designed to engage and guide the opposite edges of the binding tape in its delivery to the edge of the body fabric. 75

While the curved edge of the notch 7 evidently forms a U-shaped bending element over which the tape may be drawn transversely to the guiding or forming portion 3, as in the ordinary English binder, it is 80 preferably supplemented by a block 14 secured transversely in the mouth of the binder and having its operative surface shaped to conform with the U-shaped tape-turning edge thereof, so as to present a 85 guiding surface for the turned binding and the edge of the body fabric embraced thereby.

The base portion 1 is shown provided with the elongated apertures 15 adapted to receive the fastening screws 16 by which it is secured to the throat-plate 17 secured in the usual manner to the bed-plate 18 of the sewing machine in the head 19 of the bracket-arm of which is journaled the usual reciprocating needle-bar 20 carrying the 95 needle 21 coöperating with a suitable loop-taker beneath the bed-plate. As represented in Fig. 1, the machine is provided with feeding mechanism including the feed-dog 22 opposed to which are the main presser-foot 23 and the walking presser-foot 24 secured to the swinging presser-bar 25. 100

In the use of the attachment, the binding tape *t* may be led from the source of supply and threaded successively through the slots 105 11, 10, 9 and 8 in such manner as to rest

alternately against the concave inner and convex outer face of the guiding element 3, issuing from the aperture 8 and being drawn over the intermediate convex portion of the element 3 and transversely thereto through the notch 7 from which it passes between the throat-plate and the presser-feet, as represented in Fig. 1, the edge of the body fabric *m* being introduced between the upper and lower plies of the tape as thus formed and folded.

As shown in the drawings, the binder is designed to form a wider overlap of the tape upon the lower than the upper margin of the body fabric, and the inclination of the slots 8 and 9 and their position is such as to cause the crowding of the lower edge of the tape against the guide-pin 13 to insure uniformity in the presentation of the tape to the margin of the body fabric. To this end, these two tape-apertures are inclined downwardly and forwardly toward the delivery end of the binder and their lower extremities extend laterally at the bottom somewhat beyond their upper extremities as indicated more particularly in Figs. 3 and 4.

By the present construction, the tape *t* enters the binder in substantially flat condition and is gradually formed into U-shape cross-section by contact alternately with the taper inner and outer faces of the guiding element 3, a tension being imposed thereon by its engagement with the edges of the transverse slots. At the delivery end of the binder, the tape is abruptly arched by its passage over the part of the member 3 between the slot 8 and notch 7, so that it is at all times maintained taut at its point of delivery to the margin of the body fabric. Thus, the effective control of the tape at its point of delivery adapts the binder for operation with precision in binding the edge of a body fabric having short or abrupt curvature or angles without liability to pucker or to imperfect application of the tape so as to vary the spacing of the fastening stitches from the edges of the tape.

From the nature of the improvement as thus described, and as shown in the drawings, it is obvious that, not only is the horizontal width of the tape-guiding element 3 at its delivery end necessarily equal to or greater than the length of the adjacent transverse tape-aperture 8 and the tape issuing therefrom, but that the tape-turning edge of the notch 7 must be at least as long as the width of the tape or the length of said tape-aperture, the tape being supported throughout its width upon the convex face of the guiding element 3 to the extreme delivery end of the latter. By reference to the drawing it will be observed that the tape-aperture 8 is much closer to the extremity of the guiding element 3 than its own length, and that it therefore performs

its controlling function thereon as close as possible to the tape-turning edge of the notch 7 so as to insure precision in the ultimate delivery of the tape to the stitch-forming mechanism.

Having thus set forth the nature of the invention, what I claim herein is:—

1. A sewing machine binder constructed with a tape-guiding element having a wall formed in a single thickness substantially throughout its length and provided adjacent its delivery end with a tape-aperture extending through said wall, said element at its delivery end having a tape-turning edge of a length not less than the length of said aperture.

2. A sewing machine binder constructed with a tape-guiding element having a wall formed in a single thickness substantially throughout its length with a convex outer face and concave inner face and having a plurality of transverse slots extending through the same of which one is adjacent the delivery end, a central guide-notch being formed in the delivery end having an operative tape-turning edge of substantially the same length as the adjacent transverse slot.

3. A sewing machine binder constructed with a shell having respectively convex and concave outer and inner faces and provided with a beveled portion forming a central notch at its delivery end for inverting a tape and an adjacent tape-aperture affording communication between said inner and outer faces.

4. In an English binder, a shell or wall of U-shape cross-section having a beveled end portion for inverting a strip and provided adjacent said beveled end portion with a recess through which a strip may be passed and confined against the convex wall of the shell immediately adjacent the inverting beveled end portion.

5. An English binder consisting of a shell or single wall provided with a beveled end portion for inverting a strip and having an incisioned body portion constructed to act upon and flex in opposite directions both faces of a tape in advance of its inversion.

6. In an English binder, a sheet-metal wall bent between its edges in the shape of a U, having a beveled delivery end, and provided with a tape-guiding body portion having a plurality of incisions therein of which one is immediately adjacent the beveled delivery end whereby a strip may be led to the line of stitching in a direction at substantially right angles thereto and inverted close to the stitching point.

7. In an English binder for directing tape to the stitching point at an angle to the line of feed and inverting it into parallelism with the edge of a fabric to be bound, a single-wall-member with convex and concave faces and having a beveled delivery end,

edge-controlling fingers, and one or more recesses in the wall adjacent the beveled delivery end.

8. In an English binder, a sheet-metal wall bent between its edges in the shape of a **U** having a beveled delivery end and provided with a tape-guiding body portion having a plurality of incisions therein inclined to the vertical of which one is immediately adjacent the beveled delivery end whereby a strip may be led to the line of stitching in a direction at substantially right angles thereto and inverted close to the stitching point.
- 15 9. An English binder consisting of a shell or single-wall-member bent between its edges

to form superimposed portions of unequal width and having a beveled delivery end for inverting a strip, said shell or walled member being provided adjacent said end 20 portion with an aperture through which a strip may be passed and confined against the outer face of the shell immediately adjacent the inverting beveled end.

In testimony whereof, I have signed my 25 name to this specification, in the presence of two subscribing witnesses.

ALBERT H. DE VOE.
